UNITED STATES PATENT OFFICE.

AXEL THEODOR JACOBSSON, OF CLEVELAND, OHIO.

FRAME FOR MOVING-PICTURE SCREENS.

1,353,242.

Specification of Letters Patent. Patented Sept. 21, 1920.

Application filed April 17, 1920. Serial No. 374,585.

To all whom it may concern:

Be it known that I, AXEL THEODOR JACOBSSON, a subject of the Government of Sweden, residing at Cleveland, in the county of Cuyahoga and State of Ohio, have invented certain new and useful Improvements in Frames for Moving-Picture Screens, of which the following is a specification.

This invention relates to frames for supporting fabric screens used in connection with moving picture machines and for the purpose of receiving the image projected therefrom.

It has for its particular object to provide a light but sturdily constructed framework, preferably made of wooden strips upon which the reproducing fabric is stretched.

Heretofore it has been difficult to obtain a fabric surface which would be free from wrinkles, the common method being to provide an ordinary framework of wood and to tack the fabric about the edges. Difficulties attending this process are numerous and chief among them the impossibility of providing a surface entirely free from wrinkles.

By the means employed fabric is first tacked upon the edges of the main framework and this framework is then so manipulated as to permit of stretching the fabric sufficiently to cause it to assume a perfectly even surface.

With the above object in view the invention consists in the certain arrangement and combination of parts hereinafter illustrated in the drawings, and described and particularly pointed out in the accompanying claims.

Reference being had to the accompanying drawing wherein like reference numerals indicate similar parts throughout the various views, Figure 1 is a perspective view of the device with a portion of the fabric shown in place; Fig. 2 is a vertical section; Fig. 3 is a detail rear view of one of the joints; Fig. 4 is a perspective view, Fig. 5 is a perspective view showing the manner in which the corners are constructed, and Figs. 6, 7 and 8 are detail views showing a modified form of construction.

The invention comprises a frame composed of top and bottom members 1 and 2 and spaced from each other at their ends by the side members 3. The corners of these two members are in effect a miter joint but

to permit of movement being had with respect to each other and to prevent lateral displacement each member is provided with a tongue 4 which engages grooves 5 cut in the opposite members, the joints being loose in one direction. It will be noted that each of the corners are formed in a like manner. A supporting or inner frame comprising longitudinal strips 6 and transverse strips 7 is secured to the back of the main frame 60 and in a manner to permit of movement being had between the fabric supporting structure and itself. The strips 6 and 7 are rigid with respect to each other and at the points where they cross each other the ordinary 70 mortise joint is employed, the separate pieces being secured to each other by means of screws 8 passing therethrough. The strips 6 and 7 are secured to the supporting structure by means of blocks 10 and 75 said blocks are provided with transverse grooves 11 and 12 and said grooves are cut in a manner to provide a tongue or bridge 12^a. The ends of the strips 6 and 7 are provided with slots 14 thereby to straddle the 80 bridges 12^a when in place and the aforesaid grooves are large enough to permit of considerable play being had between the block 10 and the strips 6 and 7.

In this manner after the fabric has been 85 stretched over the strips 1, 2 and 3 and secured thereupon by tacks 15 should any wrinkles occur it is possible, by driving wedges 16 between the block 10 and the strips with sufficient pressure, to warp the 90 strips 1, 2 and 3 to an extent sufficient to perfectly smooth out all wrinkles in the fabric.

In Figs. 6 to 8 I have shown a modified form of structure comprising a frame 20 composed of top and bottom strips 21 and 22 respectively, these are joined at their ends by a mortised joint 24 and are adapted 95 to carry the fabric upon which the image is projected from the moving picture machine. The aforesaid frame is braced at 100 each of its corners by a structure which permits the frame being manipulated as in the formerly described means.

This consists in securing to each of the 105 members 21 and 22, and adjacent the end thereof, a pair of blocks 25 by means of screws or nails 26 and said blocks are provided with transverse grooves 27, these being similar to that heretofore described for 110

the blocks 10, differing only in that the grooves 27 are cut at an angle of 45 degrees and a brace 28, having its ends formed similar to the strips 6 and 7, is then interlocked with said blocks, and by driving wedges at 29, the frame may be warped into shape as previously described.

The above described construction provides a means for accomplishing the results above set forth in a quick and efficient manner, a construction which will be cheap of manufacture, extremely durable and light in weight and while I have shown and described this particular form of invention it is evident that the same is capable of being modified in various ways therefore I do not wish to limit myself in the construction of the same further than is required by the

state of the art or that which comes within the scope of the appended claim.

20

I claim:

A screen comprising an outer frame having bars with loose joints in the corners of the frame, a fabric fixed to said bars, blocks fixed to all of said bars, an inner rigid frame having crossed bars the ends of which are loosely mortised into said blocks, and wedges in the mortises, between said ends and the blocks, to expand the bars of the outer frame.

25

In testimony whereof, I do affix my signature in presence of two witnesses.

AXEL THEODOR JACOBSSON.

Witnesses:

JOHN A. BOMMHARDT,
G. V. ROSENBERG.
